UNITED STATES PATENT OFFICE.

JULIUS SCHWARZ, OF NEW YORK, N. Y., ASSIGNOR TO HANS HOHNER,
OF NEW YORK, N. Y.

MUSICAL WIND INSTRUMENT.

No. 797,232.

Specification of Letters Patent.

Patented Aug. 15, 1905.

Application filed December 2, 1904. Serial No. 235,182.

To all whom it may concern:

Be it known that I, JULIUS SCHWARZ, a citizen of Germany, residing at New York city, Bronx, county and State of New York, have invented new and useful Improvements in Musical Wind Instruments, of which the following is a specification.

This invention relates to a musical wind instrument of novel construction and designed to produce musical sounds by exhausting air from pipes and by blowing it into the same by means of a common nozzle.

In the accompanying drawings, Figure 1 is a longitudinal section through one of the cells of a musical wind instrument embodying my invention. Fig. 2 is a longitudinal section on line 2 2, Fig. 1; Fig. 3, a cross-section on line 3 3, Fig. 1; Fig. 4, a perspective view of a mouth-harmonica embodying my invention; and Fig. 5, a longitudinal section, partly broken away, on line 5 5, Fig. 4.

In carrying out my invention a mouth-harmonica or similar musical wind instrument is divided into a series of cells of the construction more fully illustrated in Figs. 1 to 3. Each of these cells has a separate mouthpiece, and by exhausting air therefrom an organ-pipe contained within one compartment of the cell is sounded. By blowing air into the same mouthpiece a second organ-pipe contained within a second compartment of the cell is sounded, the construction being such that when one of the pipes is in action the second pipe is out of action.

The letter A represents the cell of the musical wind instrument, which is divided by longitudinal partition a and transverse partitions a' a'' into a front air-chest b , a rear air-chest c , and a pair of chambers d and e between said chests.

Within the chamber d is contained a pressure-pipe f , the wind-receiving end or foot f' of which is fitted into an opening of front partition a' , so that air blown into front chest b will enter the pipe. Opposite to the rear of pipe f the rear partition a'' has an air-outlet a''' , controlled by a rearwardly-opening valve g .

Within the chamber e is contained a suction-pipe h , the wind-receiving end or foot h' of which is fitted into an opening in the rear partition a'' , so that the pipes f and h are reversely mounted. The interior of pipe h communicates, by means of its aperture h'' , with the chamber e , so that if air is exhausted from the

front of such chamber a sheet of wind will be drawn from rear chest c into pipe h and out through aperture h'' , so as to sound the pipe. Opposite to the front of pipe h the front partition a' has an air-inlet a^4 , controlled by a forwardly-opening valve i .

The front chest b has a nozzle or mouth-piece j , by which air may be exhausted from the chest or blown into the same. The rear chest c communicates permanently with the atmosphere by a port a^5 . This rear chest serves more particularly for protecting the rear valve g and may be omitted, if desired.

If air is blown into nozzle j , valve i will close to cut off chamber e from chest b and prevent the sheet of wind from entering the former. The wind will thus all pass into pipe f and out of its aperture f'' (and with open pipes through the back thereof) into chamber d , from which it will escape through open valve g , chest c , and port a^5 . In this way pipe f will be sounded by pressure, while pipe h will remain mute.

If air is exhausted through nozzle j , valve g will close to cut off chamber d from chest c , and consequently from port a^5 , and thus prevent the sheet of wind from being drawn into chamber d . The wind will thus all pass into pipe h and out of its aperture h'' (and with open pipes through the front thereof) into chamber e , from which it will pass through open valve i and chest b into nozzle j . In this way pipe h will be sounded by suction, while pipe f will remain mute.

It will thus be seen that by forcing air into or exhausting it from the chest b , or, in other words, by changing the tension of the air in said chest, either the pipe f or the pipe h will be sounded, the one by pressure and the other by suction.

In Figs. 4 and 5 is illustrated a mouth-harmonica B, divided by means of the transverse partitions k into a series of cells A, each being of the construction above described and each provided with its separate mouthpiece j . Thus by applying either air-pressure or suction to one of the mouthpieces but a single note will be sounded without necessitating the manipulation of valves.

What I claim is—

1. A musical wind instrument provided with a pair of reversely-mounted organ-pipes, and means common to both pipes for exhausting the air from one pipe and creating a blast in the other pipe, substantially as specified.

2. A musical wind instrument provided with a cell divided into a pair of chambers, an air-chest common thereto, a pair of organ-pipes reversely located one in each chamber, the foot of one pipe communicating with the outer air, the foot of the other pipe communicating with the air-chest, an outward-opening valve between the first chamber and the air-chest, a second outward-opening valve between the second chamber and the outer air, and means for changing the tension of the air in the air-chest, substantially as specified.

3. A musical wind instrument divided into a plurality of cells, an exhaust organ-pipe within each of the cells, and means for separately exhausting the air from each of the cells, substantially as specified.

Signed by me at New York city, (Manhattan,) New York, this 1st day of December, 1904.

JULIUS SCHWARZ.
